UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

FOLDING MECHANISM

Original application filed October 28, 1926, Serial No. 144,877. Divided and this application filed November 18, 1929, Serial No. 507,963. Renewed May 11, 1932.

This is a division of my application for patent on a newspaper printing machine, filed October 28, 1926, Serial No. 144,877.

This invention relates to a folding mechanism for a printing machine adapted especially for use for printing large daily papers such as are produced usually in the cities of the larger size outside of the few largest cities of the country.

10 The principal objects of the invention are to provide a folding mechanism in such relation to the press as to take up comparatively small space laterally and secure exact synchronism in its operation with the press; to 15 design the presses and folder so that their frames can be made up of separate parts united and joined to the other units without finishing the adjacent parts and avoiding the production of noise by the vibration of the 20 elements; to provide improvements in the cutting and folding cylinders, and in fact throughout the folding mechanism, whereby the web can be slit and run into the folding mechanism along different paths and delivered in either direction without having to 25 dismount the parts; and in general to so combine these several parts that a machine is secured which will run with few stoppages, comparatively little oversight and produce 30 a completed product in a uniform manner and at the same time will take up a comparatively small amount of floor space.

Other objects and advantages of the invention will appear hereinafter.

35 Reference is to be had to the accompanying drawings in which

Fig. 1 is a side view of a folding mechanism constructed in accordance with this invention;

40 Fig. 2 is an enlarged view showing the connecting parts between the folder and the nearest press unit and also the path of the web from one to the other;

45 Fig. 3 is a front view of the folder;

Fig. 4 is an enlarged view of a part of the same with the fan reversed;

50 Figs. 5 and 6 are similar views of the delivery operating as shown in Figs. 3 and 4 respectively;

Fig. 7 is an elevation of the end of the drag roll and associated parts;

Fig. 8 is an end view of the same;

Fig. 9 is a horizontal central sectional view, partly in elevation, through the centers of 55 the folding and cutting cylinders, and

Fig. 10 is an end view of the same.

I have illustrated a press unit A provided with a folder C located at the end of the printing unit. In this case, the drive is through the impression cylinder shaft 12. The shaft 12, I call the driving shaft and it is provided with an extension rigidly mounted on the end, coupled directly by a coupling 15 to a shaft 18 which drives the folder C. These driving shafts, are located at the same level, namely 60 the level of all the impression cylinders, so vertical shafts are eliminated with their gears.

This machine is set up throughout in accordance with the process set forth in my 70 Patent No. 1,498,769, granted June 24, 1924. For example it will be seen in Fig. 2 that there are a number of seats on the drawings marked 7. In each of these places the parts of the frame are connected together by the casting of the seats 7 on the two connected parts, or shafts, or rods are mounted by the casting of bearings 8 in accordance with said patent. In this way the parts of the machine are assembled without finishing and thus at a material saving in cost. Noise of 75 vibration is also reduced as it is transmitted from one part to another. I have used the numerals 7 and 8 to designate these forms of connection throughout the several sheets of 80 drawings and without reference to the shape and special construction of the various seats and bearings to which it is applied. The machine can be assembled in the old way, 85 however.

The folding machine frame 9 and the press unit are connected together by a base 4 at the bottom and by frames 6 at the top. The frames 3 and 9 carry soft metal seats 7 at 90 their lower ends having contact with similar seats on the base 4. The frame 6 is shorter than the distance between the frame 3 of the printing unit and the frame 9 of the folding unit. The surfaces that are closely adjacent 95 to each other in the assembled structure are 100

cast with depressions to be filled, instead of projections to be finished. These dovetailed depressions are used in the condition in which they are cast. The spaces between are 5 filled with soft metal in the form of seats 7 such as have been described above. The soft metal seats transmit the vibrations practically without noise and, in fact, diminishes the amplitude of vibration. Bolts are introduced through them, or other fastening devices as may be desired, but are not described herein in detail as they are shown in my prior applications and patent above mentioned.

15 By reference to Fig. 2 it will be seen that the webs W and W¹ are divided in two and I call the extra webs W² and W³. They are brought along up to the drag roll 16 in substantially the same relationship as that in 20 which they left the slitter 10, being carried over turning bars. They are separated at some point in their travel and are guided over four separate compensator rollers 17. These compensator rollers in each case are mounted 25 on levers 17^a, one end of each of which is provided with a poppet and screw thread for receiving an adjusting screw 18 which is operated by a hand wheel 19 fixed thereon. Four of these are indicated in Fig. 2 for the 30 separate adjustment of the four webs into which the two webs have been slit in the manner described. These parts are mounted on the frame 6.

The folding machine which is mounted on 35 the frame 9 has the shaft 18 previously referred to as its main shaft. This is driven from the shaft 12 of the nearest printing unit through a coupling 15 and it carries the folding cylinder. On this shaft 18 is a sprocket 40 wheel 20 which, by a chain 21 drives a shaft 16^a. The chain passes over idler sprockets 22, both mounted on a frame 23 pivoted for adjustment.

The shaft 24 is carried by brackets 25 fixed 45 to the frame by seats 7 and carries a bevel gear 26 which is driven by bevel gear 27 on the shaft 16^a. Carried by the brackets 25 at the two ends of the folding machine is a shaft 28 extending across on which are fixed arms 59, 29, arms 30 and an operating lever 31. This operating lever has an arcuate slot 32 into which extends a screw 33 having a projection at the end by which it is screwed up to hold up the lever 31 in any position in which 55 it is placed. The arm 30 has a hole through it for the pin 34 which is pressed by a spring against a shaft 35 through which the pin passes. One end of the lever 35 is bifurcated and provided with holes for carrying the 60 shaft 35^a. This shaft is free to rotate and is adapted to receive the threaded end of the pin 34. This pin has a head 36 which can be pulled down to take the pressure of a spring 37. Normally the spring forces the 65 lever upwardly at that end and forces a pro-

peller roll 38 down on the surface of the drag roll 16. It will be seen that three of these propellers 38 are shown across the machine (see Fig. 3) and they can be all operated simultaneously by the operating lever 31 and each one of them can be released by its nut or head 36 independently of the others.

This drag roll is located in position to receive half the width of web from the presses and as each web is slit in two parts it carries 75 four webs. It delivers the slit webs to the former 39 and through forming rolls 40 and nipping rolls 42. One of the latter is yieldingly pressed against the other by a spring pressed pin 43. The web goes down through 80 these between the folding cylinder 45 and the cutting and collecting cylinder 46 which constitutes a part of the couple.

It will be remembered that the folding cylinder shaft 18 is coupled by the coupling 85 15 directly to the impression cylinder shaft of the adjacent printing unit. Also the sprocket wheel 20 on the shaft 18 drives the drag roll. The shaft 18 is mounted on the frame 9 by soft metal bearings 8 at both 90 ends and also the cutting and collecting cylinder 46 has its shaft mounted on the frame by similar bearings so that there need be no finishing of the frame in order to set these shafts and cylinders in proper position 95 thereon.

The shaft 18 is provided with a gear 41 which drives a gear 44 on the shaft of the cutting cylinder 46 to drive the same. A gear 47 fixed on the shaft 18 drives a gear 48 loose on the shaft of the cutting cylinder 46. The gear 48 is provided with a cam groove 50 which operates a roll 51 on an arm 52 carried by the pin shaft 53. This shaft also has arms 54 which, in accordance 100 with the action of the cam, drives the pin rods 55. The pins operate in substantially the usual way in the usual guides. The cutting cylinder is provided with a knife 56 and cheek-block 57 which are located and 105 operated as described in my applications above identified. The folding and nipping rolls are driven by a sprocket chain 58 from a sprocket wheel 59 on the shaft of the cutting cylinder.

110 Mounted about the shaft of the folding cylinder is a cam 60 fixed on the frame and having an internal cam surface for operating two rollers 61. These rollers are on an arm 62 carried by opposite longitudinal 115 shafts 63 on the folding cylinder. Arms 64 extend outwardly on the opposite sides of these shafts and in opposite directions. They are connected together by a spring 65 across the end of the cylinder to normally hold these rollers 61 outwardly in contact with the internal cam 60. These shafts 63 also have arms 66 for operating the pin rods 67 mounted in guides 68, for performing the 120

usual function of the pins on the folding cylinder.

Also mounted on one of the soft metal bearings 8 and fixed to the frame 9 by a screw 70 is a stationary gear 71 which, as the folding cylinder rotates, operates through single intermediate, gears 72 carried by the cylinder on shafts 73. These shafts are mounted on a part of the cylinder by soft metal bearings 8 constructed like the other bearings of this kind. The shafts 73 carry the usual folding blades 74 and operate them to bring them into the proper position for folding at the bottom of the folding cylinder as is well understood in this art.

The folded product passes between a pair of folding rolls 75 centered below the folding cylinder and mounted above on two cross rods 76 by means of depending frames 77. One of these frames is fixed and the other is pressed upon by a pair of springs 78 on guide rods 79 which keep the rolls in close contact. The stationary folding roll is driven by the chain 58. The adjustable folding roll is driven from the stationary one by a pair of gears on the rear ends of the folding roll shafts.

Below the folding rolls the folded product of course is delivered to a fan 80. This fan is mounted on a shaft 81 which is driven by a chain 82 from a sprocket wheel 83 on the shaft of the cutting cylinder 46. The fan shaft is mounted in bearings on the frame 9 preferably by means of metal bearings 8 as previously described and its blades are designed as usual for receiving the folded product between them. It is shown in Figs. 4 and 6 as in position to deliver to the left. It is provided with a guide 86 which directs the product into the fan and stops the rotation of the product when it reaches the lowermost point. The upper end of the guide is fixed to one of two rods 86^a and the bottom on the shaft 91 or 91^a.

I have shown tighteners 87 for the chain 82 and 88 for the chain 89 which drives a sprocket wheel 90 from the fan belt shaft 81. The sprocket wheel 90 is on a shaft 91 on which is the counter disc 92. This counter disc has the usual notch 93 for the counting roll 94. This roll is mounted on an arm pivoted on a shaft 95 and held against the edge of the counter disc 92 by a spring 96. The spring is adjustable by means of a slot 97 in the end for a bolt by which the end is held to a lug 98 on the frame. The shaft 95 supports the guide 85 which extends up between the vanes of the fan for the usual purpose.

The delivery belts 99 are carried by a set of pulleys 100 on the shaft 91 and a set of pulleys 101 carried by a shaft mounted on a pair of brackets 102 constituting a tape delivery frame which is detachable and adapted to be fixed on either side of the main frame

9. These brackets 102 are hung on a shaft 104 or 95^a and have extended lugs 103 for engaging against the frame of the machine. On this cross shaft also are arms 105 carrying tightener pulleys 106 for the delivery belts 99. It will be seen from Fig. 6 that these parts are designed to deliver the products at the left in bunches as stated. This counter works in the usual way and the papers come down to the same and are stopped by the guide 86. They are dropped by the fan on the delivery belts 99 and bunched in bunches of fifty or one hundred, or any other number as may be provided for by the setting of the counter in its construction.

Now referring to Figs. 3 and 5 it will be seen that the delivery mechanism is reversed but the same elements are employed. In the first place the fan 80 is taken off its shaft and turned around end for end. The drive for the fan is changed so that the driving chain 82, or if desired a different chain 82^a, is driven from a sprocket wheel 81^a on the folding cylinder shaft 18. This obviously reverses the direction of the fan and causes the fan to deliver in the opposite direction. Additional changes are made as follows:

The guides 85 are taken off the shaft 95 and put on the shaft 95^a. The counter and connected parts are taken off the shaft 91, reversed, and put on the shaft 91^a. The roll 94 and its arm on the shaft 95 is placed on the shaft 95^a. It is connected as before with the spring 96 but that spring extends in the opposite direction and instead of being connected with the lug 98 it is connected with the lug 98^a on the same side of the frame. Likewise the tightener 88 which is mounted on the bolt that connects the spring with the lug is placed on the lug 98^a and performs the same function on the belt 89 as before but is on the opposite side. The chain tightener 87 also is used for the same chain 82 but in a different position. The reversal of the fan of course necessitates the reversal of the guides 86. For that purpose they are removed from the shaft 91^a and put on the shaft 91. The papers are stopped going in the opposite direction, but in the same position at the bottom of the fan by the guides 86 located in the new place.

In this way it will be seen that the reversal of the delivery can be brought about in a very simple way by turning the fan end for end and reversing the counter with its parts and the guides, etc. Also the brackets 102 are reversed and put on the other end of the machine. If it is desired to support the longer delivery belts at a point between pulleys 100 and 101, a set of pulleys 107 are used. They are mounted on brackets 108 similar to the brackets 102 pivoted on the same shaft and having lugs 109 at the bottom, performing the same functions as the lugs 103.

It will be seen therefore that the folding machine is driven directly from one of the printing couple shafts of the printing machine without intermediate gearing, that it is all mounted on one frame, and has means for driving the drag roll and carrying the products from the drag roll to the delivery belts on that frame. Also various parts are mounted on this frame by means of seats cast into place to avoid the finishing of the parts of the frame and cooperating elements. The folding and delivery of the products is done by the usual process in machines of this kind, but the reversal of the delivery is an important improvement and there are new details of construction. It will be observed that the parts are so associated as to permit of high speed and economical assembly of the machine. This folder is adapted to be set up with high speed printing press units and to receive the products of a plurality of them and deliver their products in the form of completed newspaper sections at a very high speed all counted automatically.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:—

1. In a folding machine, the combination with a former and a drag roll mounted to deliver thereto, of a series of propellers, levers on which said propellers are mounted, springs for individually operating said levers to force the propellers against the drag roll, a shaft having projections on which said levers are pivoted and provided with a handle, whereby said shaft can be turned to move all the propellers into or out of contact with the drag roll, and means for holding the handle in either extreme position, said springs being adjustable independently so that the operation of the handle will not affect their adjustments.

2. In a folding machine, the combination with a folding cylinder and a cutting cylinder, of a pair of shafts on the folding cylinder, each having arms fixed thereto and projecting in opposite directions, a spring across the cylinder for connecting two of said arms, a cam fixed in position, rolls on the other arms for engaging said cam and operating the arms in opposition to the springs, as the folding cylinder rotates, and pin rods operated by said shafts under the control of said cam.

3. In a folding machine, the combination with a folding cylinder, of a shaft on the folding cylinder having an arm fixed thereto, a spring, a cam, a roll on the arm for engaging said cam and operating the arm in opposition to the spring, as the folding cylinder rotates,

and a pin rod operated by said shaft under the control of said cam.

4. In a folding machine, the combination with the folding and cutting cylinder, of a fan for receiving the folded product therefrom, a counter cooperating with the cam, the fan being reversible to deliver in opposite directions, and means for driving the fan from the cutting cylinder shaft when the fan is to deliver in one direction and from the folding cylinder shaft when it is to deliver in the opposite direction.

5. In a folding machine, the combination with the folding and cutting cylinder, of a fan located below them for receiving the folded product therefrom, a counter cooperating with the fan, delivery belts in proper relation to the counter and fan to receive the counted products therefrom, means whereby the fan can be reversed to deliver in opposite directions, and sprocket wheels on the folding and cutting cylinder shafts for independently driving the fan from the cutting cylinder shaft when the fan is to deliver in one direction and from the folding cylinder shaft when it is to deliver in the opposite direction.

6. In a delivery for a folding machine, the combination with a fan, the fan being reversible end for end, means for driving the fan in opposite directions in its two positions, of a counter disc adapted to be reversed and mounted in either of two positions according to the direction of rotation of the fan, a counter roll, and an arm for carrying the counter roll adapted to be mounted in either one of two positions to cooperate with the fan in its two positions.

7. In a delivery for a folding machine, the combination with a fan, means whereby the fan can be reversed end for end, means for driving the fan in opposite directions in its two positions, a counter adapted to be mounted on a shaft in either of two positions according to the direction of rotation of the fan, and a counter roll, of an arm for carrying the counter roll, said arm being adapted to be mounted on a shaft in either one of two positions on the frame to cooperate with the fan in its two different positions.

8. In a delivery for a folder, the combination with a fan shaft, a fan adapted to be mounted on said shaft either end around, so that the fan may deliver in opposite directions in its two settings, two counter shafts and two counter cam roll shafts, of a counter disc and counter cam roll adapted to be changed from one shaft to the other and reversed when the fan is reversed.

9. In a delivery for a folding machine, the combination with a fan, means whereby the fan can be reversed end for end, means for driving the fan in opposite directions in its two positions, a counter adapted to be mounted on a shaft in either of two positions according to the direction of rotation of the

fan, and a counter roll, of an arm for carrying the counter roll, said arm being adapted to be mounted on a shaft in either one of two positions on the frame to cooperate with the fan in its two different positions, and a spring for holding the roll against the counter cam adapted to be reversed with the counter cam roll, said frame having two lugs in each of which the other end of the spring is secured 10 in accordance with the position of said shaft on the frame.

10. In a delivery for a folder, the combination with a frame having bearings for a fan shaft, of a fan adapted to be mounted either 15 end around, so that the fan may deliver in opposite directions in its two settings, a counter, a counter cam roll, both adapted to be changed from one shaft to another when the fan is reversed, a shaft mounted at each 20 side of the frame, and a delivery tape frame adapted to be hung on either shaft across the main frame and projecting therefrom, said frame having a shaft provided with delivery tape pulleys thereon.

25. 11. In a delivery for a folder, the combination with a fan shaft, a fan adapted to be mounted on said shaft either end around, so that the fan may deliver in opposite directions in its two settings, two counter shafts, 30 and two counter cam roll shafts, of a counter disc and counter cam roll adapted to be changed from one shaft to the other and reversed when the fan is reversed, a delivery tape frame adapted to be hung on a shaft 35 across the main frame and projecting therefrom, said frame having a shaft at its end provided with delivery tape pulleys and having lugs projecting into contact with the main frame below its pivot shaft to hold it 40 in position, and tape tightener pulleys carried by said delivery tape frame, the main frame having two shafts for said delivery tape frame at opposite sides, whereby the delivery tape frame can be transferred from 45 one side of the main frame to the other for delivery in opposite directions.

12. In a delivery for a folding machine, the combination with a main frame, of a pair of counter shafts and counter cam roll shafts, a 50 counter disc adapted to be supported in position on either counter shaft, pulleys thereon for the delivery tapes, two shafts supported in bearings on either side of the frame, a delivery tape frame adapted to be pivoted on either of the latter shafts in a position to project beyond the end of the frame, and a shaft and pulleys thereon for supporting the tapes.

55. 13. In a delivery for a folding machine, the combination with a main frame having a 60 pair of counter shafts and counter cam roll shafts, of a counter disc and delivery tape pulleys adapted to be supported on either counter shaft, a counter cam roll adapted to be carried on either of the cam roll shafts 65 for reversing the delivery, two cross shafts

supported in bearings on either side of the frame, a delivery tape frame adapted to be pivoted on either of the latter shafts, a shaft and pulleys on the delivery tape frame for supporting the tapes located beyond the side 70 of the frame, and a third frame pivoted on one of said shafts and projecting inwardly toward the counter shaft and having supporting pulleys thereon for the delivery tapes when the delivery tapes are run in one direction.

In testimony whereof I have hereunto affixed my signature.

CERTIFICATE OF CORRECTION.

Patent No. 1,883,226.

October 18, 1932.

HENRY A. WISE WOOD

It is hereby certified that error appears in the printed specification of the above numbered patent requiring correction as follows: In the heading to the specification, line 6, for Serial No. "507,963" read "407,963"; and that the said Letters Patent should be read with this correction therein that the same may conform to the record of the case in the Patent Office.

Signed and sealed this 28th day of March, A. D. 1933.

(Seal)

M. J. Moore.
Acting Commissioner of Patents.
